UNITED STATES PATENT OFFICE.

BENEDICT B. LEDERER, OF PROVIDENCE, RHODE ISLAND, ASSIGNOR TO S. & B. LEDERER COMPANY, A CORPORATION OF RHODE ISLAND.

DESIGN FOR A LOCKET.

No. 39,245.

Specification for Design.

Patented April 7, 1908.

Application filed January 25, 1908. Serial No. 412,677. Term of patent 3½ years.

To all whom it may concern:

Be it known that I, BENEDICT B. LEDERER, a citizen of the United States, residing at Providence, in the county of Providence and State of Rhode Island, have invented a certain new, original, and ornamental Design for a Locket, of which the following is a specification.

The figure is a plan view of a locket showing my new design.

I claim,
The ornamental design for a locket, as shown.

BENEDICT B. LEDERER.
